Des. 207,617
Patented May 9, 1967

207,617

CIGARETTE SNUFFER

Warren R. Damis, Bricktown, and Irvin J. Gershen, Springfield, N.J., assignors to Maggie Magnetic, Inc., Paterson, N.J., a corporation of New York

Filed June 17, 1966, Ser. No. 2,712

Term of patent 14 years

(Cl. D85—2)

FIG. 1 is an isometric view of a cigarette snuffer showing the top, front and one side of our new design;

FIG. 2 is a side elevation view of the cigarette snuffer shown in FIG. 1;

FIG. 3 is a front elevation view of the cigarette snuffer, as seen from the left of FIG. 2;

FIG. 4 is a top plan view of FIG. 2; and

FIG. 5 is a rear elevation view of the cigarette snuffer, as seen from the right of FIG. 2.

We claim:

The ornamental design for a cigarette snuffer, as shown.
